UNITED STATES PATENT OFFICE.

RICHARD H. TYNER, OF CINCINNATI, OHIO.

PORTABLE LAUNDRY-SEGREGATING BIN.

1,381,896.

Specification of Letters Patent. Patented June 14, 1921.

Application filed January 24, 1920. Serial No. 353,898.

To all whom it may concern:

Be it known that I, RICHARD H. TYNER, a citizen of the United States, and resident of Cincinnati, in the county of Hamilton and State of Ohio, have invented a certain new and useful Portable Laundry-Segregating Bin, of which the following is a specification.

The object of my invention is to provide 10 a laundry segregating bin of simple, durable and inexpensive construction.

A further object is to provide a device of 15 the class mentioned, comprising a frame mounted on suitable conveying means, whereby the device may be easily transported from place to place, and having a removable container suitably mounted thereon, and having above said container a platform and a series of spaced partitions.

Still a further object is to provide simple 20 and convenient means for forming receptacles above said platform.

In general it is my purpose to form a laundry segregating bin having a plurality 25 of receiving receptacles or compartments adapted to receive different kinds of laundry, the parts being so arranged that the laundry may be quickly and easily thrown into the different compartments or removed 30 therefrom, the entire device being readily transportable from place to place.

My invention consists in the construction, arrangement and combination of the various 35 parts of the device, whereby the objects contemplated are attained, as hereinafter more fully set forth, pointed out in my claims, and illustrated in the accompanying drawings, in which:

Figure 1 shows a side elevation of a laundry 40 segregating bin embodying my invention.

Fig. 2 shows an end elevation of the same.

Fig. 3 shows a view similar to that shown 45 in Fig. 1, the longitudinally arranged upper partitions being removed.

Fig. 4 shows a vertical sectional view taken on the line 4-4 of Fig. 3.

Fig. 5 shows a horizontal sectional view taken on the line 5-5 of Fig. 1, and

Fig. 6 shows a similar view taken on the line 6-6 of Fig. 1.

It is well known that one of the important problems which must be solved in every laundry is that of quickly and accurately 55 sorting the different articles of laundry that

may come indiscriminately mingled in a large bundle. For convenience in sorting laundry many expedients have been employed. It is my purpose to provide a portable segregating bin of the kind above 60 mentioned, comprising a frame, preferably rectangular in its general outline, and having at its corners the uprights which I have indicated in the drawings herewith by the reference character 10.

At the upper and lower ends of the uprights 10 are fittings 11 and 12 respectively. The uprights 10 are connected at their lower ends by longitudinal frame members 13 and transverse frame members 14, and at their 70 upper ends by similar longitudinal and transverse members 15 and 16 respectively. The frame members above referred to are preferably ordinary tubing or pipe connected by ordinary fittings.

It may be mentioned that the uprights 10 are supported at their lower ends by suitable 75 caster wheels 17, which are mounted on and connected with the main frame by suitable ball bearings 18 which facilitates the easy 80 moving of the bin from place to place.

Suitably mounted at the lower ends of the members 10 and spaced a proper distance 85 above the floor on which the device rests, are opposite, transversely arranged angle 90 bars 19 clearly shown in Figs. 1 and 3, forming guides and tracks for a large laundry receiving box 20 having the rollers 21 adapted to travel on the horizontal flanges of the angle irons 19. The box 20 has a plurality 95 of transverse partitions 22 whereby the box is divided into a plurality of compartments A, B and C. The upper part of the side of the box 20 adjacent to the respective compartments is cut away somewhat, as shown 100 at 23 and 25, for affording openings to receive the laundry.

Suitably connected with the fittings 11 and extending upwardly at the four corners of the device, are upright members 26 preferably of tubes or piping. The upright members 26 have at their upper ends elbows 105 27. The members 26 at each end of the bin are connected at their upper ends by transverse tubes 28, as shown in Fig. 2.

Intermediate of the uprights 10 at each side of the machine fittings 29 are mounted on the frame members 15 in suitable spaced 110 relation to each other and the end members 16, and extending upwardly from fittings

29 are upright members 30 similar to the members 26. The members 30 on one side of the device are alined with the respective members 30 on the other side of the device, 5 and the alined members 30 are suitably connected at their upper ends by elbows 27 similar to those already described, and transverse pipes or tubes 31. The elbows at one end of the tubes are removed from Fig. 10 1 to show the ends of the tubes 31.

Suitably mounted on the uprights 26 and 30 above the members 16 and 15 is a platform 33.

15 The opposite members 30 are connected by suitable partitions 34. In this connection it may be mentioned that the fittings 29 are capable of sliding on the frame members 15, and may be locked in a variety of positions by set screws 35, so that the partitions formed by the uprights 30 and the partition members 34 may be varied in position with relation to each other and to the ends of the device. The platform 33 is provided with elongated slots 36 to permit the longitudinal sliding of the uprights 30.

30 It will thus be seen that in the practical use of my improved segregating bin different classes of laundry may be thrown into the various compartments A, B and C, and also into the spaces between the partitions 34. Partitions 37 may be placed between the successive uprights 26 and 30 and between the uprights 30 at the sides of the machine, for making walls for the compartments above the platform 33.

40 The partitions 34 and 37 may be secured in position by the following means: For securing the partitions 34 in position there is mounted on each member 26 and 30 a yoke 38 held in position by a screw 39 extended through the yoke and through the upright 26 or 30, as the case may be. The yoke 38 has formed near one end thereof the outwardly extending, spaced, parallel flanges 40 adapted to receive between them the edge of the partition.

45 In Fig. 6 I have shown one of the yokes for holding one of the partitions 34 in position. Similar yoke members 38 are used, as shown in Fig. 1, for receiving the outer edges of the partition members 37.

50 For supporting the members 37 on the uprights 30 I provide yokes 41 held in position on the uprights 30 by means of screws 39 similar to those already described. The yokes 41 have at their opposite ends spaced parallel pairs of flanges 42, as shown in Fig. 5, for receiving the edges of opposite partition members 37. It will be seen that the partition members 37 may be slid upwardly or downwardly for removing them, if desired, without removing the yoke members 41.

55 60 65 On one side of the box 20 are suitable han-

dles 32 which may be grasped for conveniently sliding the box 20 into and out of the frame.

In the practical use of my improved segregating bin the bin may be used with or 70 without the partition members 37. Assuming that the device is used without said members 37, the different kinds of laundry are thrown into the compartments A, B and C and onto the platform 33 between the successive partition members 34. If desired partition members 37 may be used at one side of the device while the other side may be left open between the successive partition members 34. 75 80

It will be seen that the laundry may thus be readily separated and classified, and that the laundry pieces thus separated may be easily moved from place to place by moving the entire segregating bin on the caster 85 wheels 17.

The parts are of extremely simple and durable construction.

The bin may be made in different sizes with any desired number of compartments. 90

Changes may be made in the construction and arrangement of my improved device and the parts thereof, and it is my intention to cover by my present application any modified forms of structure or use of mechanical equivalents which may be included within the reasonable scope of the claims of the patent to be issued hereon. 95

I claim as my invention:

1. In a device of the class described, a 100 frame comprising upright corner members, means for connecting said corner members near their lower ends, means for connecting said corner members near their upper ends, opposite supporting guides mounted on the 105 lower portion of said frame members, a receptacle supported on said guides, upright members at the corners of said device at the upper end of said first named corner members, a platform supported on said frame 110 above said receptacle, upright members capable of adjustment to a variety of positions, said platform being provided with slots 115 to receive said last named upright members, and partition members for connecting the 115 opposite adjustable members.

2. In a device of the class described, a frame, a platform thereon spaced between the top and bottom of said frame, a movable receptacle mounted on the lower portion of said frame, transverse partitions above said platform, intermediate upright members at the sides of said frame above said platform, partition members connecting the intermediate upright members on the opposite sides 120 of said device, and removable partition members for forming walls at the sides of said device above said platform. 125

3. In a device of the class described, a frame, a slidable receptacle supported on the 130

- lower portion of said frame, a platform above said receptacle, upright members at the sides of said frame between the ends thereof, capable of adjustment longitudinally of the frame, said upright members being extended through said platform, said platform being provided with slots to permit the adjustment of said upright members, partition members for forming compartments above said platform, and means for connecting said partition members with said upright members, said means including a yoke having at each end a pair of outwardly extending parallel flanges.
- 5 10 15 4. In a device of the class described, a frame, a slideable receptacle supported on the lower portion of said frame, a platform above said receptacle, upright members at the sides of said frame between the ends thereof, capable of adjustment longitudinally of the frame, said upright members being extended through said platform, said platform being provided with slots to permit the adjustment of said upright members, partition members for forming compartments above said platform, means for connecting said partition members with said upright members, and means for connecting said partition members with the frame above said platform, said last means including a yoke having at one end a pair of outwardly extending parallel flanges.
- 20 25 30

Des Moines, Iowa, November 9, 1916.

RICHARD H. TYNER.
